UNITED STATES PATENT OFFICE.

ARTHUR C. HERTHEL, OF ST. LOUIS, MISSOURI.

CIGAR MOISTENER.

Application filed September 14, 1920. Serial No. 410,295.

To all whom it may concern:

Be it known that I, ARTHUR C. HERTHEL, a citizen of the United States, residing at the city of St. Louis, in the State of Missouri, have invented certain new and useful Improvements in Cigar Moisteners, of which the following is a specification.

This invention is primarily a cigar-moistener and secondarily, an advertising device. It may be used in any place or for any purpose where it is desired to conduct or exhale moisture, and its size and arrangement may be varied according to circumstances. As shown in the drawings, its use is contemplated more particularly in connection with a showcase for cigars and the like in which or in connection with which it may be located.

In the accompanying drawings forming part of this specification, in which like numbers of reference denote like parts wherever they occur,

Figure 1 is a side elevation;

Figure 2 is a sectional view through one of the end members;

Figure 3 is a sectional view, taken on the line 3—3 in Figure 1, looking in the direction indicated by the arrows;

Figure 4 is a top plan view of part of this device;

Figure 5 is a top plan view of the wick, with advertisements in position;

Figure 6 is a similar view with but one advertisement; and

Figure 7 is a sectional view, taken on the line 7—7 in Figure 4, looking in the direction indicated by the arrows.

A plurality of Mason jars 1 is suitably located and supported relative to the objects or place to be humidified. Larger or smaller jars may be used in place of Mason jars, according to circumstances. The number of jars may, also, be varied, from one up, according to need and desire. Ordinarily, it will be found most convenient for the wick 2 to lead from one jar to another, although it can be arranged to lead back to the same jar from which it rises. Furthermore, if the showcase or other place to be humidified is so long that the weight of the wick 2 tends to cause it to sag, an intermediate jar may be used as a support and will generally be necessary, also, as an additional source of moisture.

Water or the like is placed in each jar 1, and capillary attraction causes it to rise in wick 2 and to travel along the length of the wick. When two jars 1 are used, as shown in the drawings, the moisture from one jar will in its travel meet the moisture from the other about the middle of the length of wick 2.

The top of each jar 1 is preferably threaded at 3 and so, also, is the bottom of each collar 4, so that collars 4 can be screwed on the tops of jars 1. This permits removal of the wick-bearing members or cylinders 5 and the wick 2 without disturbing or removing the jars 1, which can be refilled with water from the top when thus freed or may be removed for that purpose. By means of a syringe or the like, the jars 1 can be refilled through slots 6 without removing anything.

Collars 4 are loosely mounted on and revolvable around cylinders 5, and thereby the size of slots 6 can be enlarged or diminished. Some evaporation takes place through slots 6, and the regulation of their size affects the degree of humidity in the cigar showcase or other place where jars 1 stand.

The collars 4 are vertically-slidable on cylinders 5, which permits their rotation notwithstanding the screw-threads at 3 on the jars 1 and the collars 4.

Cylinders 5 are borne by an attaching frame 7, adapted to be attached by screws through holes 8 to a showcase or other support.

Slots 9 permit the wick 2 and its siderods 10 to be inserted from either side of frame 7. The siderods 10 are shaped as best seen in Figures 3 and 7, their ends resting within frames 7. The main body of wick 2 is supported by them like a bridge, and the tails or ends of wick 2 descend from the opposite ends into jars 1, as shown in Figure 1.

The siderods 10 are so constructed that the side edges of wick 2 are crimped between them. Wick 2 is composed of process cotton 11 or the like, inclosed in a sleeve or bag 12, within the longitudinal edges of which extend round cords 13. Flange 14 is crimped against the edge of sleeve 12 in such manner (as best seen in Figure 3) as to clasp cord 13 as contained within sleeve 12. Aperture 15 is too small for cord 13

to escape therethrough. This binds wick 2 to siderods 10 in a secure but removable manner.

Advertisements may be attached in any desired number or manner to wick 2. Figure 6 shows but one such advertisement for one of these devices. Figure 5 shows a plurality of such advertisements located between the frames 7, but within one show-case 16.

Straps 17 are either bent out from frame 7 or attached thereto in order to hold the ends of siderods 10, which are thus stationarily but removably attached to frame 7.

15 While the cords 13 have been mentioned as round, yet all that is necessary is that they shall be of such thickness as will not permit their withdrawal through the openings 15.

20 The frames 7 are reversible, in the sense that it is immaterial which slot 9 receives wick 2.

Flange 18 limits movement of collar 4 and cylinder 5 with relation to each other. Cylinder 5 may be formed integral with frame 7, as shown in the drawing, but in any event will be suitably attached thereto.

Screws 19 fasten the top of frame 7 to the woodwork 20 of the showcase 16. The 30 advertisements on wick 2 show through the glass 21.

As illustrated particularly in Figure 7, each tubular support 10 is split longitudinally so that the edges of the same may 35 securely grip the edge portions of the wick. When the end portions of the tubular body 10 are inserted into the openings defined by the straps 17 and the adjacent portions of the frames 5 the edges of the tubular bodies are drawn in the direction of each 40 other so that the wick will be firmly gripped.

The advertising matter may be applied directly to the upper exposed side of the wick or to the upper edges of the rods 10 45 in a manner to effectively conceal the wick from the view of one looking down on the showcase in which the humidor is installed.

Having thus described this invention, I hereby reserve the benefit of all changes in 50 form, arrangement, order, or use of parts, as it is evident that many minor changes may be made therein without departing from the spirit of this invention or the scope of the following claims.

55 I claim:

1. A humidifier comprising liquid containers, frames connected to said containers and having means whereby the same may be connected to a display case, a wick passed 60 through said frames into said containers, and longitudinally split tubular supports receiving the edges of said wick and firmly gripping the same.

2. A humidifier comprising liquid containers, attaching frames connected to said

containers, a wick passed through said frames into said containers, and a longitudinally split tubular support receiving the edge portion of said wick and firmly gripping the same, the ends of said tubular support being detachably connected to said frames.

3. A humidifier comprising liquid containers, frames connected to said containers and having means whereby the same may 75 be connected to a display case, a wick passed through said frames into said containers, and longitudinally split spaced tubular supports receiving the edges of said wick and firmly gripping the same, said wick constituting an attaching means for display matter adapted to conceal said wick.

4. A humidifier comprising frames having openings, longitudinally split tubular supports having their end portions received in said openings and their edges urged together by contact of the supports with the walls of said openings, and a wick having its edge portions received in said tubular supports and gripped by the edges of said supports.

5. In a device of the character described, an elongated wick and a pair of linear supports therefor adapted to clamp the opposite side edges of the said wick, and means 95 for supplying moisture to the opposite ends of said wick.

6. In a device of the class described, an elongated wick, a pair of elongated supports disposed in spaced parallel relation, the wick extending along said supports and having its ends depending from the opposite ends thereof, and means for supplying moisture to the opposite free ends of said wick.

7. A humidifier comprising a receptacle adapted for the reception of water, an attaching frame supporting said receptacle and having a depending cylinder, a collar rotatably carried by said cylinder, and a 100 wick supported by said frame and extending through said cylinder into said receptacle, said collar being provided with means controlling the circulation of air through said cylinder.

8. In a device of the class described, an elongated wick, a pair of linear supports disposed at the opposite sides of said wick and adapted to sustain a major length of the intermediate portion of the wick in a horizontal position with its opposite free ends depending therefrom, and means for supplying moisture to the free ends of said wick.

9. In a device of the class described, a 125 frame, a cylinder depending from said frame and having openings therein, a collar adjustable on said cylinder, a water container removably supported from the lower end of said collar, said collar having open-

ings therein adapted to be moved into and out of registry with openings of said cylinder for regulating the degree of evaporation of the water in said water container there- 5 through, and a wick supported in said frame and having an end thereof depending through said cylinder and dipping into the water in said water container.

10. A device of the character described, comprising a plurality of frames, a cylinder depending from each of said frames, a water container supported from each of said cylinders, a wick extending between said cylinders and depending therethrough into said 15 water container, grooved metal supports for the intermediate portion of said wick, and straps carried by said frame for sustaining said supports in position.

11. A device of the character described, comprising a plurality of attaching frames, a cylinder depending from each of said frames, collars encircling said cylinders said collars having their lower ends screw-threaded, a water container engaged on the 25 threaded end of each of said collars, a wick extending between said cylinders, and depending therethrough and into said water containers, supports for sustaining the intermediate portion of said wick in a horizontal 30 plane, and straps carried by said frames for securing said supports in position.

12. A device of the class described, comprising a plurality of attaching frames, a cylinder depending from each of said frames and having openings in the walls thereof, a collar surrounding each of said cylinders, and a water container attached to each of 35 said collars, said collars having openings therein whereby, upon a revolving movement 40 being imparted to the said collars, the said openings thereof will register to a greater or lesser degree with the openings in said

cylinders for correspondingly varying the effects of evaporation of the water within said containers.

45

13. A device of the class described comprising a plurality of attaching frames, a cylinder depending from each of said frames and having openings in the walls thereof, a collar surrounding each of said cylinders, 50 a water container attached to each of said collars, said collars having openings therein adapted to be moved into and out of registry with the openings of the latter, and a wick leading laterally into each of said frames 55 and having their inner ends depending through said cylinders and dipping into the water contained in said water containers.

14. A humidifier of the class described, comprising a pair of spaced water receptacles, a wick extending between said receptacles and having its opposite ends dipping into the water contained therein, and means for supporting the intermediate portion of 60 said wick in position.

65

15. A humidifier of the class described, comprising a horizontally extended wick, means engaging the opposite side edges of said wick and supporting the same in its extended position, and means for supplying 70 moisture to the opposite ends of said wick.

70

16. A humidifier of the class described, comprising a wick having the intermediate portion thereof extended in a horizontal plane and the opposite end portions thereof 75 depending in angular relation with respect thereto, means for sustaining the intermediate portion of said wick in its extended position, and means for supplying moisture to the opposite ends of said wick.

80

In testimony whereof I hereunto affix my signature.

ARTHUR C. HERTHEL.
